UNITED STATES PATENT OFFICE.

CLARENCE MAYER AND SAMUEL YAFFE, OF CHICAGO, ILLINOIS, ASSIGNEES TO
NATURE'S RIVAL COMPANY, OF CHICAGO, ILLINOIS, A CORPORATION OF ILLINOIS.

FORM-PADS.

1,018,066.

Specification of Letters Patent.

Patented Feb. 20, 1912.

Application filed June 27, 1910. Serial No. 568,979.

To all whom it may concern:

Be it known that we, CLARENCE MAYER and SAMUEL YAFFE, citizens of the United States, and residents of Chicago, in the county of 5 Cook and State of Illinois, have invented certain new and useful Improvements in Form-Pads; and we do hereby declare that the following is a full, clear, and exact description thereof, reference being had to the 10 accompanying drawings, and to the letters of reference marked thereon, which form a part of this specification.

This invention relates to a garment provided with bust pads for filling out and 15 modifying the bust portions of the human figure.

The object of the invention is to provide an article of apparel in the form of what is generally known as a corset cover having a 20 part covering the bust which is provided with pockets adapted to contain pads which hold the waist in a definite form which simulates the human bust, and to provide an improved construction of pad which will hold 25 its shape without inflation, thereby greatly reducing the cost of such pads.

The invention consists of the matters hereinafter described and more particularly pointed out in the appended claim.

30 In the drawings—Figure 1 is a perspective view of the human figure with a corset cover provided with our improved pads in position thereon. Fig. 2 is a perspective view on an enlarged scale of one of the pads. 35 Fig. 3 is a partial section through Fig. 1 on the line 3—3 thereof, shown on a slightly larger scale than that of Fig. 1. Fig. 4 is a section through Fig. 2 on the line 4—4 thereof on the same scale as that of Fig. 2. Fig. 40 5 is a partial section similar to Fig. 4 on an enlarged scale.

A indicates the waist or corset cover which may be of any usual or convenient construction, and is adapted to be worn above the 45 corset. It has the usual shoulder straps *a*, *a* which hold it in proper position with reference to the shoulders. Said waist is provided near its upper front margin with pockets *B*, *B* located so as to lie over the 50 bust and conformed to receive the elongated

pads *C* which are of a shape and size to give the desired fullness to the bust.

In that embodiment of the invention illustrated herein, each pad *C* comprises a front member *C*¹ and a rear member *C*². The 55 front member *C*¹ is preferably made of a plurality of pieces, in this case three, *c* *c*¹, *c*², which are cut to give said front member the desired rounded appearance. Said pieces are seamed together, as indicated at *c*³, *c*³. 60 In the front member *C*¹ are formed a plurality of long, narrow pockets *b* which are arranged close together and extend generally in a vertical direction. In the pockets *b* are located ribs *b*¹ which are made of 65 whale-bone, light wood or any other suitable elastic material, which is adapted to hold the pocket in distended form. The rear member *C*² is secured at its margins to the margins of the front member *C*¹ and is of 70 smaller extent than the front member. The rear member thus draws the margins of the front member toward each other, as clearly to be seen in Figs. 3 and 4. This draws the 75 ends of the ribs toward each other, so as to maintain them in bent relation, thereby maintaining the required rounded front of the front member *C*¹.

It is apparent that by properly proportioning the sizes and shapes of the front and rear members, any desired form may be attained and that the rear member will hold the front member in this desired form permanently. This construction does away with the necessity for inflating the pads, and 85 makes it possible to dispense with the use of rubber or other inflatable material, thereby greatly reducing the cost of the pads.

The front and rear walls of the pockets *B* are basted together at their upper margins as indicated at *b*² after the pads are in place and when it is desired to launder the 90 waist the basting threads may be removed and the pads taken from the pockets. The parts themselves are made of any suitable 95 flexible material.

We claim as our invention:—

The combination with a waist provided with a bust portion having pockets, of pads adapted to be placed in said pockets em- 100

bracing a front wall, stiffening means provided in said front wall, and a rear wall secured at its margins to the margins of the front wall, said rear wall being of less extent than the front wall, and being adapted to maintain said front wall in the desired form.

In testimony that we claim the foregoing

as our invention we affix our signatures in the presence of two witnesses, this 24th day 10 of June A. D. 1910.

CLARENCE MAYER.
SAMUEL YAFFE.
